UNITED STATES PATENT OFFICE.

GEORGE JACOB EPPRIGHT, OF MANOR, TEXAS.

SHUTTER ATTACHMENT.

SPECIFICATION forming part of Letters Patent No. 665,733, dated January 8, 1901.

Application filed October 2, 1900. Serial No. 31,784. (No model.)

To all whom it may concern:

Be it known that I, GEORGE JACOB EPPRIGHT, a citizen of the United States, and a resident of Manor, in the county of Travis and State of Texas, have invented a new and Improved Shutter Attachment, of which the following is a full, clear, and exact description.

The purpose of this invention is to provide means for holding the slats of window-shutters open, the invention being applicable to those shutters which have a number of horizontally-arranged slats pivoted and connected with a bar which may be moved to move the slats to open or closed position.

This invention is the disclosure of several forms of the invention, while the claims define the actual scope thereof.

Reference is to be had to the accompanying drawings, forming a part of this specification, in which similar characters of reference indicate corresponding parts in all the views.

Figure 1 is a front view of a window-shutter to which my invention is shown as applied. Fig. 2 is an enlarged vertical section showing the invention in use. Fig. 3 is a horizontal plan view with parts in section on the line 3 of Fig. 1. Fig. 4 is a vertical section of a modified form of the invention, and Fig. 5 is

30 a perspective view of a further modification.

The device comprises a spacer, which is pivotally mounted on the slat-bar in position to be moved between two of the slats when they are open and which serves when in such position to prevent the movement of the slats on their pivots, and consequently to prevent the slats from closing. Referring to Figs. 1, 2, and 3, this spacer is indicated by the letter *a* and is there shown to be constructed of a

40 piece of wire bent to form two horizontal parts at its top and bottom, which respectively engage the adjacent faces of two of the slats of the window-shutter. This spacer is pivotally mounted through the medium of a sleeve or

45 other fastening *b* on the slat-bar. In the drawings the slat-bar is indicated by the letter *c* and the slats by the letter *d*. Now it is

clear that the spacer may be moved to the position shown in Fig. 2, so as to hold the slats from movement, and since all of the slats are connected with the slat-bar the whole series of slats is held. It is also clear that by moving the spacer to the position indicated at the right-hand side of Fig. 1 the slats will be free to swing to closed position.

55

Fig. 4 shows an arrangement in which the spacer *a'* is arranged to straddle two contiguous slats and to engage the distant faces thereof, as contradistinguished from engaging the near faces. With this form of the invention the principle is precisely the same as that before described.

Fig. 5 shows the spacer *a''* arranged to act in the same manner as in Figs. 1, 2, and 3. In Fig. 5, however, the spacer is shown to be 65 constructed of an unbroken metallic plate rather than of a piece of wire bent into the requisite form.

Having thus described my invention, I claim as new and desire to secure by Letters 70 Patent—

1. A shutter attachment, comprising a spacer mounted on the shutter removably to engage between the side faces of two or more slats, to hold the slats open in the manner 75 specified.

2. A shutter attachment, comprising a spacer pivotally mounted on the slat-bar and arranged to engage two or more of the slats to prevent the slats from closing.

80

3. A shutter attachment, comprising a spacer constructed of a length of wire to form two horizontally-disposed parts, the spacer being movable between two of the slats and being pivotally mounted on the slat-bar, for 85 the purpose specified.

In testimony whereof I have signed my name to this specification in the presence of two subscribing witnesses.

GEORGE JACOB EPPRIGHT.
